UNITED STATES PATENT OFFICE.

ROBERT BINNIE, SR., OF BOLIVAR, PENNSYLVANIA.

ROCK-DRILL.

No. 818,015.

Specification of Letters Patent.

Patented April 17, 1906.

Application filed August 26, 1905. Serial No. 275,906

To all whom it may concern:

Be it known that I, ROBERT BINNIE, Sr., a resident of Bolivar, in the State of Pennsylvania, have invented a new and useful Improvement in Rock-Drills; and I do hereby declare the following to be a full, clear, and exact description thereof.

This invention relates to rock-drills; and its object is to provide a simple, strong, durable, and efficient device of this character which is driven by a motor mounted directly thereon.

The invention resides in details of construction and arrangement hereinafter described and claimed.

In the accompanying drawings, Figure 1 is a side elevation of my improved rock-drill. Fig. 2 is a vertical section of the drill body or casing. Fig. 3 is a similar section on the line 3 3, Fig. 1. Fig. 4 is a horizontal section on the line 4 4, Fig. 1. Fig. 5 is a similar section on line 5 5, Fig. 1. Fig. 6 is a rear view of the motor and its mounting. Figs. 7 and 8 are detail views of the cushioning means for the motor-trunnions. Fig. 9 is a detail of gear-casing and motor-casing neck. Fig. 10 is a sectional view of connection for pitman-rod, and Figs. 11, 12, and 13 are detail views of the tripod.

My improved drill comprises a suitable support or tripod 1, having secured thereto the backbone or guide 2, which is adapted to be set vertically or in any other position, according to the direction of the hole to be drilled. This backbone is provided with suitable ways 3, on which is slidably mounted the drill body or casing 4. A screw 5 is rotatably mounted in the backbone 2, so as to be incapable of longitudinal movement there-
in, as by means of collar 5^a, and engages a suitable nut 6, connected to the drill-body. This screw serves to feed the drill to its work and may be actuated either by means of a handle 7 or automatically, as will be herein-
after described.

In the drill-body is mounted the vertical reciprocating drill-spindle 9, which at its lower end carries a socket or chuck 10 for receiving the drill-bit 11. This drill-spindle is guided by a bushing 12 in the lower end of the casing and by a sleeve 13, rotatably mounted in the upper end of the casing. Mounted in the casing and extending transversely of the spindle is the driving-shaft 14, which is provided with a crank 15 for receiving the connecting-rod 16, which at its

lower end is of angle shape, so as to provide a cup 17, which loosely encircles the drill-spindle 9. Also loosely surrounding the drill-spindle and resting in the cup 17 is a flanged collar 18. Interposed between this collar and a collar 19, keyed to the drill-spindle, is a spiral spring 20. Also loosely surrounding the spindle below the cup 17 is a collar 21, and interposed between this collar and the stationary collar 22 on the drill-spindle is a spiral spring 23. The upper and lower faces of the cup on the end of the connecting-rod 16 are spherical, as shown, so that the connecting-rod can rock freely and without undue friction on the collars 17 and 21.

The collars 17 and 21 and interposed lower end of the connecting-rod are free to move on the drill-spindle, and the motion of said connecting-rod is communicated to the spindle through the springs 20 and 23, thus giving a yielding or cushioned blow to the drill-spindle.

The connecting-rod is fastened to the crank 15 by means of a U-shaped strap 26, which passes around the crank and has its ends connected to the pitman-rod 16 by means of the keys 26^a and 27.

The upper end of the spindle projects through the sleeve 13, as stated. The spindle and the opening of the sleeve are square in cross-section or of other irregular shape, so they must turn in unison. The sleeve 13 has cast therewith or connected thereto a worm-wheel 30, which meshes with a worm 31 on the driving-shaft 14. The rotation of said shaft therefore imparts a slow rotary movement to the sleeve 13 and likewise to the drill-spindle.

The projecting upper end of the spindle is inclosed by means of a cap 32. The extreme upper end of the spindle has secured thereto a collar 33. On said spindle between said collar and the upper end of the casing 4 is a ring or sleeve 34, provided on one side with an arm 35, pivoted on a pin 36 in the cap 32. On the opposite upper edge of the ring is a slight boss 37, with which the collar 33 on the spindle will contact in the downward movement of the spindle. Pivoted to the lower edge of the ring 34 is a pawl 38, which is adapted to engage a ratchet-wheel 39, secured to the nut 6, working on the adjusting-screw 5. A spiral spring 40 is connected to this pawl and to the cap 32 and serves not only to hold the end of the pawl in engagement with the ratchet-wheel, but also serves

to withdraw the pawl and tilt the ring 34 to the position shown in Fig. 3, swinging the same around its pivot 36, so that the opposite edge 37 thereof will be elevated. Consequently on the downstroke of the spindle the collar 33 will strike the boss 37 and swing the ring on its pivot 36, thus pushing on the pawl 38 and rotating the ratchet-wheel 39. As soon as the spindle rises the spring 40 will draw the pawl 38 backwardly and swing the sleeve 34 on its pivot 36 to the inclined position shown for the next actuation by the collar 33. This step-by-step rotation of the ratchet-wheel is communicated to the nut 6 and acts to feed the drill-body on the backbone in a well-understood way.

The crank-shaft 14 is driven by means of a motor mounted directly on the drill body or casing 4. This motor may be of any suitable type, but preferably will be an electric motor, as illustrated. This motor is shown at 42. Its armature-shaft is arranged transversely of the drill-spindle and is provided with a pinion 42^a, which meshes with the idler 43, which in turn meshes with the gear 44 on the end of the driving-shaft 14. All of these gears are straight or spur gears, so that friction is reduced to a minimum, and the proper mesh of said gears is not affected by the endwise vibration of the armature-shaft. This manner of mounting and connecting the motor has many advantages over prior arrangements, wherein the motor-shaft has been connected to the driving-shaft by interposed beveled gears.

The motor-casing is provided with trunnions 46, which are mounted in the arm of a yoke 47, secured to the drill body or casing 4. The ends of the arms of this yoke are provided with seats 48 for receiving bearings 49, surrounding the trunnions 46. Spiral springs are interposed between the bearings 49 and the yoke, so as to cushion these trunnions in all directions. Preferably these springs will surround plungers 50, as illustrated in Figs. 7 and 8. Also surrounding the trunnions 46 and interposed between the motor-body and the yoke are suitable cushions, such as rubber rings 52, which cushion any vibration of the motor axially of the trunnions. The motor-body therefore is thoroughly cushioned against the movement due to the vibration of the drill-spindle.

To permit the ready removal of the motor, the ends of the yokes are closed by means of clamping members 54, hinged at one end to the yoke and being clamped in closed position at their opposite end by means of a link 55, provided with the actuating-handle 56. Either the member 54 or the link 55, or both, are provided with inclined or cam faces.

The gears 42, 43, and 44 are inclosed by a suitable gear case or shield 60, which is removably secured to the drill-body 4 by means of bolts 60^a. This gear-casing on its

inner side is provided with a flange 61, which surrounds the neck 62 of the motor-body. One portion of this flange is stationary, while another portion 63 is hinged, as at 64, (see Fig. 9,) and is locked by means of a latch 65. Bearing against the neck of the motor are a pair of curved plates 66 and 67, and interposed between these plates and the flanges 61 and 63 are spiral springs 68, which at their inner ends bear against the plates and are seated in sockets 69, formed in plugs 70, screwed into openings formed in the flanges 61 and 63, so that by turning said plugs the tension of these springs can be varied. Rivets 71 unite the plates, springs, and plugs. These springs act to cushion the neck of the motor-casing and to hold the same yieldingly, thus preventing undue shock or vibration between the gears 42 and 43. The gear 43 is mounted on a pin 72 in the gear-case 60.

The motor is mounted directly on the drill-body and is fed with the same as the drilling progresses. It is thoroughly cushioned against jar and vibration, is so mounted that it can be quickly removed when desired, and is connected to the driving-shaft 14 by very simple gearing which cannot get out of order, which is not affected by the vibration of the motor-shaft, and which runs with a minimum amount of friction, thus preventing loss of power and overheating, and also dispensing with the troublesome flexible or sliding shafts heretofore used.

For drilling upwardly a spiral spring 73 is interposed between the chuck or socket 10 and the lower end of the drill-casing. When doing deep drilling, however, this spring is removed and in place thereof use is made of a spring for counterbalancing the weight of the additional length of drill. This counterbalancing-spring is shown at 75 and is located at the rear of the body and between the same and the backbone 2. At its upper end it is connected to a hook or lug 77 on the body 4, and at its lower end it is provided with a loop 78, which is connected to a hook 79, loosely surrounding the drill-spindle between the upper end of the socket or chuck 10 and a collar 80, clamped to the drill-spindle. This spring counterbalances the excessive weight of heavy or long drills, and therefore relieves the actuating-springs 20 and 23 of the crushing effect of this weight. It makes it possible to drill very deep holes. Said spring at its lower end is confined by the guides 81.

The tripod 1 is provided with three legs, as shown, each of which is a tube split at its lower end, as shown at 83, to receive the extensible foot-rods 84, which are clamped in position by means of nuts 85, working on the threaded split lower end of the tubes. The weights 86 are provided with U-shaped recesses for embracing the legs 1 and are held in place merely by gravity. They are provided with ribs 87, which serve as handles for re-

moving the same. The head 88 of the tripod is provided with circular end portions 89 for receiving straps 90, which surround the same and the ends of which are adapted to be 5 pressed together by means of bolts 91. These same bolts serve to secure to said strap the forward legs of the tripod. The head is also provided with two rearwardly-projecting arms 93, between which is pivoted a socket 10 member 94, in which is secured the upper end of the rear leg of the tripod. The rear leg is capable only of a swinging movement around its pivot 95, while the front legs can swing around the necks 89 and also have a lateral 15 swinging movement around the bolts 91. Secured to the head, between the arms 88, is a member 97, which is formed in two sections hinged at their lower ends by means of the bolt 98 and at their upper ends being clamped 20 together by means of a bolt 99. This bolt 99 also passes into the backbone 1 of the machine, and thus supports the same and permits the backbone to be set at any angle, so that the drill can point in any direction.

25 The drill-feeding mechanism and drill-actuating mechanism are not claimed in this application, but are claimed in my application, Serial No. 219,127, filed August 1, 1904.

What I claim is—

- 30 1. In a drill, the combination of a support, a drill body or casing movably mounted thereon, a reciprocating drill-spindle mounted in said casing, an actuating-shaft for said spindle also mounted in the casing, a motor mounted directly on the casing on trunnions at right angles to the actuating-shaft, cushioning means between said trunnions and the casing, and gearing connecting said motor and drill-actuating shaft.
- 40 2. In a drill, the combination of a support, a drill body or casing movably mounted thereon, a reciprocating drill-spindle mounted in said casing, an actuating-shaft for said spindle mounted in the casing, a motor mounted directly on the casing on trunnions at right angles to its shaft and with its shaft parallel to the actuating-shaft, cushioning means between the motor trunnions and casing, and gearing connecting said motor and drill-actuating shaft.
- 50 3. In a drill, the combination of a movable body or casing, a drill-spindle mounted therein, an actuating-shaft therefor, a motor mounted on the casing on trunnions transverse to its shaft and with its shaft parallel to the drill-actuating shaft, spur-gears connecting said shafts, and cushioning means for the motor-shaft adjacent to said gears and arranged to permit one of said gears to roll on 55 the other.
4. In a drill, the combination of a movable body or casing, a drill-spindle mounted therein, an actuating-shaft therefor, a motor mounted on the casing on trunnions transverse to its shaft and with its shaft parallel to 60

the actuating-shaft, spur-gears connecting said shafts, cushioning means between the motor trunnions and casing, and cushioning means for the motor-shaft adjacent to the gears.

5. In a drill, the combination of a support, a drill body or casing movably mounted thereon, a reciprocating drill-spindle mounted in said casing, an actuating-shaft therefor, a motor, the motor-shaft and actuating-shaft 70 being transverse to the line of reciprocation of the drill, gearing connecting said shafts, trunnions on said motor, a yoke on the casing provided with bearings for said trunnions, and cushioning means between said yoke and trunnions.

6. In a drill, the combination of a support, a drill body or casing movably mounted thereon, a reciprocating drill-spindle mounted in said casing, an actuating-shaft therefor, 85 a motor provided with trunnions, seats on the casing for receiving said trunnions, cushioning means between said seats and trunnions, gearing connecting the motor-shaft with the drill-actuating shaft, and cushioning 90 means for said motor adjacent to said gearing.

7. In a drill, the combination of a support, a drill body or casing movably mounted thereon, a reciprocating drill-spindle mounted 95 in said casing, an actuating-shaft therefor, a motor, said motor-shaft and actuating-shaft being transverse to the line of reciprocation of the drill, gearing connecting said shafts, trunnions on the motor-body, seats 100 on the casing for receiving said trunnions, cushioning means between said seats and trunnions, and cushioning means for the motor-shaft adjacent to said gearing.

8. In a drill, the combination of a support, 105 a drill body or casing movably mounted thereon, a reciprocating drill-spindle mounted in said casing, an actuating-shaft therefor, a motor yieldingly mounted on the casing and movable therewith, gearing connecting 110 said motor and drill-actuating shaft, and springs supporting said motor adjacent to said gearing.

9. In a drill, the combination of a support, 115 a drill body or casing movably mounted thereon, a reciprocating drill-spindle mounted in said casing, an actuating-shaft therefor, a motor, gearing between said motor and actuating-shaft, trunnions on said motor, seats on the casing for receiving said trunnions, 120 springs between said trunnions and seats, and springs bearing against the motor-body adjacent to the gearing connecting the same to the drill-actuating shaft.

10. In a drill, the combination of a support, 125 a drill body or casing movably mounted thereon, a reciprocating drill-spindle mounted in said body, an actuating-shaft therefor, a motor, gearing connecting the same with said drill-actuating shaft, trunnions on said 130

- motor, bearings on the casing for receiving said trunnions, said bearings being provided with a movable cap, and cam-actuated means for locking said cap in position.
11. In a drill, the combination of a support, a drill body or casing movably mounted thereon, a reciprocating drill-spindle mounted in said casing, an actuating-shaft therefor, a motor, gearing connecting said motor and drill-actuating shaft, trunnions on said motor, bearings on the casing for receiving said trunnions, a hinged cap for said bearings, and cam-actuated locking means for the free end of said cap.
12. In a drill, the combination, of a body or casing, a reciprocating drill-spindle mounted therein, a motor for actuating said spindle, said motor being provided with trunnions, bearings for said trunnions, said bearings being provided with a movable cap, and cam-actuated locking means for said cap.
13. In a drill, the combination of a casing or body, a reciprocating drill-spindle therein, a motor for actuating said spindle, trunnions on said motor transverse to its axis, seats on the casing for receiving said trunnions, cushioning means between said seats and trunnions, and a yielding support for the end of the motor-casing.
14. In a drill, the combination of a body or casing, a reciprocating drill-spindle mounted therein, a motor for actuating said spindle, trunnions on said motor transverse to its axis, bearings for said trunnions, seats on the casing or body for receiving said bearings, and springs interposed between said bearings and seats.
15. In a drill, the combination of a body or casing, a reciprocating drill-spindle mounted therein, a motor for actuating said spindle, trunnions on said motor, bearings for said trunnions, seats in the casing for receiving said bearings and spring - pressed plungers mounted in said seats and contacting with said bearings.
16. In a drill, the combination of a movable body or casing, a drill-spindle mounted therein, a motor for actuating said spindle, trunnions on said motor, bearings for receiving said trunnions, a movable cap for said bearings, and spring-pressed plungers mounted in said bearings and caps and bearing against said trunnions.
17. In a drill, the combination of a movable body or casing, a reciprocating drill-spindle therein, an actuating-motor mounted on the casing with its shaft transverse to the line of reciprocation of the drill-spindle, trunnions on the motor at right angles to its shaft, and cushioning means arranged to cushion the movement of the motor both transversely and axially of said trunnions.
18. In a drill, the combination of a movable body or casing, a reciprocating drill-spindle mounted therein, a motor flexibly mounted on said casing, gearing connecting the motor-shaft with the drill-spindle, a flange or ring surrounding the end of the motor-body, and spring-pressed plates between said ring and the motor-body and serving to cushion the same.
19. In a drill, the combination of a movable body or casing, a reciprocating drill-spindle mounted therein, a motor trunnioned on said body, cushioning means for said trunnions, a ring surrounding the end of neck of the motor-body, spring-pressed plates interposed between said ring and motor-body, and gearing connecting the motor-shaft with said drill-spindle.
- In testimony whereof I, the said ROBERT BINNIE, Sr., have hereunto set my hand.
